UNITED STATES PATENT OFFICE.

THOMAS W. COUGHLIN, OF BINGHAMTON, NEW YORK.

BODY-REST FOR CASKETS.

SPECIFICATION forming part of Letters Patent No. 661,635, dated November 13, 1900.

Application filed March 30, 1900. Serial No. 10,858. (No model.)

To all whom it may concern:

Be it known that I, THOMAS W. COUGHLIN, a citizen of the United States, and a resident of Binghamton, in the county of Broome and 5 State of New York, have invented certain new and useful Improvements in Head and Body Rests for Caskets, of which the following is a specification.

The object of my invention is to provide an 10 improved head and body rest for caskets.

In the drawings forming part of this specification, Figure 1 is a perspective view. Fig. 2 is a cross-section. Fig. 3 is a transverse section showing the arrangement of the supporting-legs. Fig. 4 is a detached view of 15 one of the sets of legs.

The main part of the support is formed of a piece A, which may be of wood or any suitable material, having at its lower end hinged 20 pieces B, by which it is secured to the bottom of the casket. At the sides near the upper end are handles C for manipulating the support. These handles, as shown, are made of wire and are secured to the support in any 25 suitable manner. The adjustable headpiece D is secured to the rest near the upper portion thereof. As shown in Fig. 1, it is formed of a piece of wire bent into circular shape, the ends of the wire being twisted together, as 30 shown at E, the extreme end being turned out to form the pintles F. These pintles are connected to the piece A, so as to form a hinged joint, as clearly shown in Figs. 1 and 2. Pivoted at one side of the piece A is a bar or rod 35 G, which has at the center a portion H, bent at an angle, as shown, and at the other end is bent upward to form the operating-handle I. It will be seen that as this rod is moved one way or the other the head-rest D will be 40 raised or lowered and that by the construction shown the said head-rest will be maintained in any position in which it may be put. The movement of the rod is limited by the staple J. Secured to the under side of the 45 support in any suitable manner is a rod or bar K, which runs transversely thereof. Hinged to this bar are a series of legs L of different lengths. These legs may be formed in any suitable manner, though I prefer to 50 make them as shown in Fig. 4, and the number of the sets of legs may be as desired. Pivoted to the under side of the piece A is an

operating device M, which is of the form shown in Fig. 3. It is preferably made of wire and is hinged to the piece A by means 55 of a staple, through which the wire passes, the upper end of the wire being formed into an operating-handle M.

In use this device is secured to the bottom of the casket by means of tacks, screws, &c., 60 passing through the pieces B, and after the body is placed in the casket it may be adjusted by raising the rest by the handles C until the desired angle of inclination is reached. The rest is then supported by one of the legs L, depending upon the height to which it has been raised. The headpiece D is separately adjusted by moving the rod G one way or the other. If it is desired to adjust the body higher, all 65 that is necessary is to lift the rest by the handles, when the longer legs will come automatically into operation, as will be clearly seen from an inspection of the drawings. If it is desired to lower the body, the rest is lifted slightly by the handles, and then by moving 70 the operating device M by its handle N the leg supporting the rest is thrown out of engagement with the bottom of the casket and the rest may be lowered. Releasing the pressure on the handle N as the rest is being lowered 75 will cause one of the pairs of the shorter legs to assume the position where they will automatically engage with the bottom of the casket.

It will be seen that by this device the entire operations necessary for adjusting the body to different positions may be performed without the necessity of inserting the hands beneath the body or beneath the rest.

It will be obvious that but one leg may be 85 used, if so desired, the end of the same being formed so as to engage with the material of the bottom of the casket, and that by setting this leg at different angles different degrees of adjustment may be reached and maintained, 90 as the rest is prevented from endwise movement by the fastening devices B. This is illustrated in Fig. 1.

What I claim, and desire to secure by Letters Patent, is—

1. In a rest for caskets, the combination of 100 a frame or support, legs pivoted to said frame or support to support the same at different angles, and means carried by the frame for

engaging with and throwing the supporting legs out of operative position, substantially as described.

2. In a rest for caskets, the combination of a frame or support, legs of different lengths pivoted to said frame or support to support the same at different angles, and means carried by the frame for engaging with and throwing the supporting-legs out of operative position, substantially as described.

3. In a rest for caskets, the combination with a frame or support for the body of a head-rest pivoted thereto, and a lever pivoted to said frame and adapted to adjust and hold the head frame or support in the desired position, substantially as described.

4. In a rest for caskets, the combination with a frame of a head-rest pivoted to said frame, and a lever pivoted at one end to one side of the frame and extending transversely thereof, said lever having thereon means for engagement with the pivoted head-rest, whereby motion of the lever will adjust and support the said pivoted rest, substantially as described.

Signed at Binghamton, in the county of Broome and State of New York, this 26th day of March, 1900.

THOMAS W. COUGHLIN.
